US0D1052640S

(12) **United States Design Patent** (10) **Patent No.:** **US D1,052,640 S**
(45) **Date of Patent:** **** Nov. 26, 2024**

(54) **GLASSES**

(71) Applicant: **LUXOTTICA S.R.L.**, Agordo (IT)

(72) Inventors: **Matteo Cesare Battiston**, Milan (IT);
Fabio Verdelli, Milan (IT)

(73) Assignee: **LUXOTTICA S.R.L.**, Agordo (IT)

(**) Term: **15 Years**

(21) Appl. No.: **29/806,865**

(22) Filed: **Sep. 7, 2021**

(30) **Foreign Application Priority Data**
